(57) **CLAIM**

The ornamental design for a hockey stick, as shown and described.

DESCRIPTION

FIG. 1 is a perspective view of a hockey stick in accordance with a first embodiment of our new design.

FIG. 2 is a front elevational view of the design of FIG. 1.
FIG. 3 is a first side elevational view of the design of FIG. 1.
FIG. 4 is a second side elevational view of the design of FIG. 1, opposite the first side.

FIG. 5 is a rear elevational view of the design of FIG. 1.

FIG. 6 is a top plan view of the design of FIG. 1.

FIG. 7 is a bottom plan view of the design of FIG. 1.

FIG. 8 is a detailed perspective view of the blade of the hockey stick of FIG. 1, taken from region 8-8 of FIG. 1.
FIG. 9 is a detailed front elevational view of the blade of the hockey stick of FIG. 1, taken from region 9-9 of FIG. 2.

FIG. 10 is a detailed front elevational view of the blade of the hockey stick of FIG. 1, taken from region 10-10 of FIG. 5.

FIG. 11 is a perspective view of a hockey stick in accordance with a second embodiment of our new design.

FIG. 12 is a front elevational view of the design of FIG. 11.

FIG. 13 is a first side elevational view of the design of FIG. 11.
FIG. 14 is a second side elevational view of the design of FIG. 11, opposite the first side.

FIG. 15 is a rear elevational view of the design of FIG. 11.

FIG. 16 is a top plan view of the design of FIG. 11.

FIG. 17 is a bottom plan view of the design of FIG. 11.

FIG. 18 is a detailed perspective view of the blade of the hockey stick of FIG. 11, taken from region 18-18 of FIG. 11.

FIG. 19 is a detailed front elevational view of the blade of the hockey stick of FIG. 11, taken from region 19-19 of FIG. 12.

FIG. 20 is a detailed front elevational view of the blade of the hockey stick of FIG. 11, taken from region 20-20 of FIG. 15.

FIG. 21 is a perspective view of a hockey stick in accordance with a third embodiment of our new design.

FIG. 22 is a front elevational view of the design of FIG. 21.

FIG. 23 is a first side elevational view of the design of FIG. 21.
FIG. 24 is a second side elevational view of the design of FIG. 21, opposite the first side.

FIG. 25 is a rear elevational view of the design of FIG. 21.

FIG. 26 is a top plan view of the design of FIG. 21.

FIG. 27 is a bottom plan view of the design of FIG. 21.

FIG. 28 is a detailed perspective view of the blade of the hockey stick of FIG. 21, taken from region 28-28 of FIG. 21.

FIG. 29 is a detailed front elevational view of the blade of the hockey stick of FIG. 21, taken from region 29-29 of FIG. 22.

FIG. 30 is a detailed front elevational view of the blade of the hockey stick of FIG. 21, taken from region 30-30 of FIG. 25.

FIG. 31 is a perspective view of a hockey stick in accordance with a third embodiment of our new design.

FIG. 32 is a front elevational view of the design of FIG. 31. FIG. 33 is a first side elevational view of the design of FIG. 31. FIG. 34 is a second side elevational view of the design of FIG. 31, opposite the first side.

FIG. 35 is a rear elevational view of the design of FIG. 31. FIG. 36 is a top plan view of the design of FIG. 31.

FIG. 37 is a bottom plan view of the design of FIG. 31.

FIG. 38 is a detailed perspective view of the blade of the hockey stick of FIG. 31, taken from region 38-38 of FIG. 31.

FIG. 39 is a detailed front elevational view of the blade of the hockey stick of FIG. 31, taken from region 39-39 of FIG. 32; and,

FIG. 40 is a detailed front elevational view of the blade of the hockey stick of FIG. 31, taken from region 40-40 of FIG. 35. Any parts shown in broken lines form no part of the claimed design.
